PORTABLE ELECTRIC OVEN

Kurt T. Beyrodt, Williston Park, N.Y., assignor to Ref
Manufacturing Corporation, Mineola, N.Y., a corpo-
ration of New York

Filed Apr. 6, 1960, Ser. No. 60,059

Term of patent 3½ years

(Cl. D81—25)

FIG. 1.

FIG. 2.

FIG. 4.

FIG. 3.

Fig. 1 is a perspective view of the portable electric oven showing my new design,

Fig. 2 is a top plan view of Fig. 1,

Fig. 3 is a front elevation of Fig. 1, and

Fig. 4 is a side elevation of the portable electric oven opposite to that side shown in Fig. 1, while the rear of the portable electric oven, not shown, is substantially plain.

I claim:

The ornamental design for a portable electric oven, as shown and described.
